PORTABLE TRAFFIC SIGN AND SIGNAL LIGHT

Victor W. Hoye, New Castle, Pa.

Application October 20, 1953, Serial No. 27,241

Term of patent 14 years

(Cl. D72—1)

To all whom it may concern:

Be it known I, Victor W. Hoye, a citizen of the United States, residing at 306 Ridge Ave., New Castle, State of Pennsylvania, have invented a new, original, and ornamental Design for a Portable Traffic Sign and Signal Light, of which the following is a specification, reference being had to the accompanying drawing, forming a part hereof.

Fig. 1 is a front view of a portable traffic sign and signal light, showing my new design;

Fig. 2 is an end view of the same; and

Fig. 3 is a top plan view.

The dominant features of my design are shown in solid lines.

I claim:

The ornamental design for a portable traffic sign and signal light, as shown and described.
